UNITED STATES PATENT OFFICE.

DONALD F. TOUSEY, OF MINNEAPOLIS, MINNESOTA, ASSIGNOR OF ONE-HALF TO JOHN F. CANNEY, OF SAME PLACE.

GAGE-COCK.

SPECIFICATION forming part of Letters Patent No. 274,994, dated April 3, 1883.

Application filed August 9, 1882. (No model.)

To all whom it may concern:

Be it known that I, DONALD F. TOUSEY, a citizen of the United States of America, residing at Minneapolis, in the county of Hennepin and State of Minnesota, have invented certain new and useful Improvements in Gage-Cocks, of which the following is a specification, reference being had therein to the accompanying drawings.

10 My invention relates to gage-cocks for steam-boilers.

It consists in a hollow plug having threads on its forward and rear ends. The front end of the plug screws into the boiler-head. The 15 thread on the rear end receives a packing-nut. A hollow plunger works horizontally in a longitudinal circular chamber in the plug. A collar rigidly fixed on the inner side of the plug, near the center, fits closely around the 20 plunger and divides the chamber into two compartments. The rear part contains packing and ring, which are secured by the nut aforesaid. The forward end of the plunger is provided with a collar, which moves freely in 25 the front compartment. In the plunger, near its collar, are a series of perforations. Steam is permitted to circulate freely in the chamber in the boiler end of the plug. The plug is counterbored, so that there is sufficient space 30 between the periphery of the plunger-collar and the chamber-wall for the free passage of steam. To the rear end of the plunger is secured a tube having a right-angled nozzle. The tube screws into the plunger. A perforated plate 35 is formed integral on the neck of the tube, and a wooden block or wheel is secured thereto by means of screws.

I desire to term the device a "hollow-plunger gage-cock."

40 The object of my invention is to enable an engineer, by a gentle pressure of the hand, to determine the height of water in his boiler. It will be seen that by pressing on the wooden wheel the plunger is forced forward in the 45 plug, and the perforations in said plunger thereby brought in communication with the steam, so that an opening is effected, whereby the steam is permitted to pass through the perforations into the plunger and out the tube 50 and nozzle. By releasing the hand from the

wheel, the plunger is forced back by the boiler-pressure, so that the plunger-collar will rest against the inner collar in the plug. The perforations in said plunger are thereby driven outside of the packing, so that steam communication is effectually cut off. It must be obvious that after the engineer has "tried the water" in the boiler the gage-cock closes automatically and returns to its normal position. A small collar is placed on the tube to prevent the plunger from being pressed in by the hand beyond that point.

55 Figures 1, 2, and 3 are central longitudinal sections of my gage-cock, showing a fragment of the boiler in each figure. Figs. 1 and 2 represent the cock open, and Fig. 3 shows the position of the parts when closed.

60 Similar letters refer to similar parts throughout the several views.

A represents the plug. B is packing of cotton, twine, or rubber; and C, the packing-ring. D is a packing-nut, that screws onto the rear end of the plug and secures the ring and packing. E is the hollow plunger that works in the plug A. F is the neck of tube J. G is 70 a collar rigidly united to and forming a part of plunger E. G' is a collar on the tube, which acts as a stop and limits the extent to which the plunger can be inserted into the plug. H is the boiler-head. I is the right-angled nozzle on tube J. K are threads on the forward end of tube J, and K' are the threads on the inner side of the rear end of the plunger. The threads K and K' engage and unite 75 the plunger and tube. M M are threads, by means of which the plug A is secured to the boiler. O represents the series of perforations in the forward end of the plunger. P are threads in packing-nut D, by means of which the nut is secured to the plug. R is a perforated plate formed integral on tube-neck F. S are the screws by means of which the block or wheel T is united to plate R.

80 Having thus described my invention, I claim as new and desire to secure by Letters Patent— 95

1. In a gage-cock, a hollow tubular plunger having perforations in its boiler end and a collar thereon, said collar being adapted to work within a chamber in communication with the inner side of the boiler, the diameter of the 100

chamber being larger than the circumference of the collar, whereby an annular space is formed for the admission of steam to the perforations in the plunger when said plunger is 5 pressed in, the outer end of the plunger being provided with inner threads, in combination with an outside threaded tube and nozzle, the tube engaging the plunger by means of the threads, said tube being provided with a circumferential flange or collar to prevent the 10 nozzle from being driven against the outer face of the packing-nut, substantially as described, and for the purposes specified.

2. A nozzle and plunger, formed separately, 15 and united by screw-threads, the plunger having perforations adapted to communicate with the steam in the plug-chamber, said plunger, nozzle, and connecting means being hollow

and communicating from the mouth of the nozzle to a point near the inner collar, substantially as described, and for the purposes specified.

3. The combination of the hollow plunger E, having perforations O and collar G, the chamber-plug A, ring C, and nut D, the collar G 20 moving freely in the chamber and admitting steam around its sides to the openings O when said collar is moved forward in the chamber, substantially as set forth and specified.

In testimony whereof I affix my signature in 25 presence of two witnesses.

DONALD FERRIS TOUSEY.
